UNITED STATES PATENT OFFICE.

MATTHEW ALLAN, OF VICTORIA, BRITISH COLUMBIA, CANADA, ASSIGNOR OF ONE-THIRD TO WILLIAM ALFRED BLAKE, OF VICTORIA, BRITISH COLUMBIA, CANADA.

DESIGN FOR AN ASH-TRAY.

51,568.

Specification for Design.

Patented Dec. 18, 1917.

Application filed September 14, 1917. Serial No. 191,476. Term of patent 14 years.

To all whom it may concern:

Be it known that I, MATTHEW ALLAN, a citizen of Canada, residing at Victoria, British Columbia, Canada, have invented a new, original, and ornamental Design for Ash-Trays, of which the following is a specification, reference being had to the accompanying drawing, forming a part thereof, and which shows a perspective view of the ash tray.

I claim:—

The ornamental design for an ash tray, as shown.

MATTHEW ALLAN.

Witnesses:

GEORGE K. COMSTOCK,
PETER A. SWEENEY.
